UNITED STATES PATENT OFFICE.

WILLIAM ABRAHAM EDWARDS, OF PINE BLUFF, ARKANSAS.

DINNER-PAIL.

985,020.

Specification of Letters Patent. Patented Feb. 21, 1911.

Application filed May 2, 1910. Serial No. 558,878.

To all whom it may concern:

Be it known that I, WILLIAM ABRAHAM EDWARDS, a citizen of the United States, and a resident of Pine Bluff, in the county of 5 Jefferson and State of Arkansas, have made certain new and useful Improvements in Dinner-Pails, of which the following is a specification.

My invention relates to improvements in 10 dinner pails, and it consists in the combinations, constructions and arrangements herein described and claimed.

An object of my invention is to provide a 15 device in which there are a number of separate trays for carrying articles of food, with means for ventilating each tray.

A further object of my invention is to provide a device in which the trays are readily 20 accessible, with means for locking them when in position.

A further object of my invention is to provide a carrying means for liquids, this carrying means being arranged on the outside 25 of the main frame of the device in such a manner that they cannot be removed until the cover is raised.

Other objects and advantages will appear 30 in the following specification and the novel features of the device will be particularly pointed out in the appended claims.

My invention is illustrated in the accompanying drawings in which similar reference characters indicate like parts in the several views and in which—

35 Figure 1 is a perspective view showing the trays assembled in the frame; Fig. 2 is a central longitudinal section through the device; Fig. 3 is a perspective view of the main frame; Fig. 4 is a perspective view showing 40 the trays and the inner cover, and Fig. 5 is a view of the carrying case.

In carrying out my invention I provide a main frame like that shown in Fig. 3. This frame, as will be seen from the drawings, 45 consists of a bottom 1, having a flange 2 at its edges. The flange is provided with the integral upright portions 3 which are joined together at their tops, on one side, and at the two ends, by the members 4. It will be 50 noted that the end members 4 are shorter than the end members 2, the end uprights 3 being centrally disposed of the device.

An outside cover 5 is hinged to the side member 4 and is provided with the end extensions 5^a and 5^b. On the inner side of 55 the cover 5 may be arranged holders for va-

rious articles. Thus 6, designates a holder for toothpicks, 7 for matches, 8 for a comb, and 9 for a mirror. To the outside of the cover are attached the pivoted hooks 5^c. 60 The cover 5 is provided with a wire loop 10 which is adapted to enter the wire loop 11, of a triangular locking member 12, which is pivotally connected to one of the side members 2 at 13, as shown in Figs. 1 and 3. 65

The trays are shown in Fig. 4. The bottom tray 14 is of rectangular shape of greater depth than the other trays. The central tray 15 is provided with the longitudinal partition 16, while the upper tray 17 is provided with a transverse partition 18. Each of these trays is provided with screened ventilating windows. Secured in the upper tray is an alcohol lamp 19 of any suitable form. While I have described a series of 70 trays of a particular form, it will be understood that the form of the trays may be varied. The inner cover 20 is provided with the spring members 21 and 22 at the ends of the device. These are soldered or otherwise 75 secured to the cover at one end and are free at their other ends, being bent upwardly as shown in the drawing, and being provided on their ends with the loops 21^a and 22^a respectively. This cover has a bail 23. 80

Referring now to Figs. 1 and 2, it will be seen that I have provided the cans 24 and 25 at opposite ends of the device. These cans have hooks 24^a and 25^a respectively, which are arranged to be inserted in the 85 respective sockets 24^b and 25^b, which are secured to the central end members 3.

The carrying case is shown in Fig. 5. It consists preferably of a box 26 made of heat resisting and water resisting material, and 90 having a flap 27 arranged to be locked by a locking device 28 to the side of the case. It is also provided with a strap 29 for convenience in carrying it on the shoulder of the owner. 95

From the foregoing description of the various parts of the device, the operation thereof may be readily understood. The various articles of food are placed in their proper receptacles and the trays are assembled within the main frame as shown in 100 Figs. 1 and 2. The inner cover 20 is placed above the cap 19^a of the lamp 19 and the outer cover 5 is pressed down against the springs 21 and 22. The locking member 12 105 is then swung inwardly so that the eye or loop 10 passes through the loop 11. Now 110

when the pressure is relieved, the tension of the inner springs 21 and 22 of the cover forces the loop 10 to the upper part of the eye, thereby preventing these two members from becoming disengaged. The receptacle 24 which is designated to contain alcohol for the lamp 19, and the receptacle 25, which may contain any liquid such as coffee or tea, have been previously inserted in the sockets. The caps of these liquid receptacles, it will be noted from Fig. 2, lie underneath the respective extensions 5^a and 5^b and are therefore prevented from disengagement from the sockets even if the pail should be overturned. The pressure of the inner cover 20 on the cap 19^a of the lamp 19 prevents the cap from coming off. Moreover, the pressure is transmitted from one tray to the other so that the trays are held securely in place. The ventilating windows 14^a, 15^a and 17^a maintain a good circulation of air in the trays.

The frame, bearing the trays, is designed to be carried in the carrying case 26. When the device is to be used, the case may be unlocked and the device may be drawn out by means of the lifting hooks 5^c. By pulling forwardly now on the member 12, the locking member 10 may be released so as to allow the cover to be swung upwardly, as shown in Fig. 3. This will permit the receptacles 24 and 25 to be removed, and will allow the trays also to be removed. By swinging the locking member 12 downwardly, access is permitted to the trays from

the front. This I consider one of the special features of my invention.

I claim:—

1. A dinner pail comprising a main frame, having a bottom and uprights on its rear side and on its ends, a cover provided with centrally disposed extensions at opposite ends thereof, centrally disposed sockets secured to said end uprights, receptacles carried in said sockets, a locking member on said main frames adapted to lock said cover in position, whereby the receptacles are prevented from withdrawal from their sockets by the extensions on the cover. 45

2. In a dinner pail, a main frame provided with a bottom and having uprights on its rear side and its ends, sockets carried by said end uprights, receptacles normally disposed in said sockets, a cover hinged to the rear side member, having extensions adapted to project over the receptacles held in said sockets, a series of ventilated trays, an inner cover disposed above the uppermost of said ventilated trays, springs secured to the upper side of said inner cover, and a locking member pivotally mounted on the bottom member of the frame, and adapted to hold the cover of said main frame in engagement with the springs on said inner cover for keeping said trays 65 in position. 55

WILLIAM ABRAHAM EDWARDS.
